UNITED STATES PATENT OFFICE.

THOMAS C. OLIVER, OF CHARLOTTE, NORTH CAROLINA.

PROCESS FOR PRODUCTION OF SULFURIC ACID IN LEAD CHAMBERS.

1,229,316.

Specification of Letters Patent. Patented June 12, 1917.

Application filed February 7, 1917. Serial No. 147,203.

To all whom it may concern:

Be it known that I, THOMAS C. OLIVER, a citizen of the United States, residing at Charlotte, in the county of Mecklenburg and State of North Carolina, have invented a new and useful Improved Process for Production of Sulfuric Acid in Lead Chambers, of which the following is a specification.

This invention relates to apparatus for use in the production of sulfuric acid in lead chambers. It is a well known fact that various cooling means have heretofore been devised for use in connection with the chamber process of acid production but the cooling apparatus used has generally been objectionable because of the cost involved in the installation and operation thereof.

One of the objects of the present invention is to provide cooling means which can be readily installed, does not require the use of any intricate or expensive apparatus, will effectively cool the contents of the chamber, and can be regulated readily to give the most effective cooling action.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the apparatus has been illustrated.

In said drawings:

Figure 1 is a vertical section through the apparatus.

Fig. 2 is a section on line 2--2 Fig. 1.

Fig. 3 is an enlarged vertical section through a portion of the reservoir and adjacent parts.

Fig. 4 is an enlarged section on line 4--4 Fig. 3.

Referring to the figures by characters of reference 1 designates the chamber of the apparatus having lead walls 2 suitably fastened to spacing and supporting columns 3 which are attached in any desired manner to the walls 4 of the housing or building in

which the chamber is located. The chamber is provided with the usual conical top 5 to the apex of which is extended the gas inlet pipe 6. A gas outlet pipe 7 extends from the lower portion of the chamber. The housing or building 4 is extended over and spaced from the top or dome 5 of the chamber and has a draft pipe or stack 8 extending therefrom. The supporting columns 3 serve to separate the space between the walls of the chamber 1 and the building 4 into separate passages 9 all of which communicate at their upper ends through the space 10 between dome 5 and the top of housing 4 with the flue or outlet 8.

A reservoir 11 is arranged in the lower portion of the housing or building 4 and the lower portions of the lead walls 2 are extended inwardly and downwardly into the reservoir as shown. A partition 12 extends outwardly from the upper edge of the wall of the reservoir to the wall of the housing or building 4 so that an annular space 13 is thus provided around the reservoir. This space is in communication with a blower casing 14 through a flue 15. Outlet openings 16 are formed in the partition 12 below each of the passages 9 and each of these openings is adapted to be partly or entirely closed by a damper 17 which can be of any construction desired and which can be supported in partly open position by a toothed segment 18 or by any other suitable means. The wall of the housing or building 4 is also provided close to the partition 12 with openings 19, one of these openings being preferably provided for each of the passages 9. By means of these openings air can be admitted to the lower ends of the passages from the outside of the apparatus. Each opening 19 has a damper 20 for controlling the flow of air therethrough. This damper may be held in open position in any suitable manner, as by means of links 21.

It is to be understood that gas is directed through the lead chamber in the usual manner and cooling of the contents of the chamber is effected by the circulation of air between the wall of the housing or building 4 and the lead walls 2 of the chamber 1. It is a well known fact that when air is used as a cooling medium its efficiency is depend-

ent upon its velocity. For example if, at a velocity of 2 feet per second, the transmission coefficient is 1, under the same conditions the coefficient will be 4 when the velocity is 15 feet per second. In other words, when the air is traveling 15 feet per second it will be four times as efficient as a cooling medium than if traveling at a velocity of 2 feet per second. It is upon this basis that 5 the present cooling arrangement has been devised. When the atmospheric conditions permit it the dampers 20 are opened and the cool air from the surrounding atmosphere will be drawn through these openings and 10 into the respective passages 9 through which it will flow upwardly at a high velocity due to the draft set up. Thus the contents of the chamber will be quickly and effectively cooled without requiring the installation of 15 expensive and intricate cooling apparatus. Where the atmospheric conditions will not permit the use of the outside air as a cooling medium, the dampers 20 can be closed and dampers 17 opened, whereupon by actuating the blower in the casing 14, air can be forced into the annular chamber 13 which will distribute it to the various openings 16 thus causing the air to be supplied to the 20 various passages 9 through which it will 25 rush at the desired velocity to the draft pipe or flue 8. Obviously if desired both sets of dampers 20 and 17 can be opened at the same time. By adjusting the dampers a proper amount of cooling air can be introduced to the passages 9.

What is claimed is:

1. Apparatus for use in the production of sulfuric acid, including a chamber having lead walls, a housing extending around and 40 over said chamber and providing separate air passages along the outer surface of the wall of the chamber, an outlet flue in communication with the upper ends of the passages, and means for directing air into the 45 lower ends of the passages.

2. Apparatus for use in the production of sulfuric acid, including a chamber having lead walls, and air passages extending along the outer surfaces of said walls and having 50 inlets at their lower ends and an outlet at their upper ends.

3. Apparatus for use in the production of sulfuric acid, including a lead chamber, a housing inclosing the chamber and forming 55 air passages extending along the outer surface of the walls of the chamber, said passages being provided with air inlets at their lower ends, and an outlet flue in communication with the upper ends of the passages

60 whereby a natural draft is created through the passages and along the walls of the chamber.

4. Apparatus for use in the production of sulfuric acid in lead chambers, including a

lead chamber, a reservoir at the lower end 65 thereof, there being an air space around the reservoir, a housing surrounding the lead chamber and forming separate air passages extending upwardly along the outer surface of the walls of the lead chamber, means for 70 controlling communication between the annular air space and the lower ends of the respective air passages, means for directing air under pressure into the annular air space, and an outlet flue in communication 75 with the upper ends of the air passages.

5. Apparatus for use in the production of sulfuric acid, including a lead chamber, a housing surrounding said chamber and forming separate air passages extending upwardly along the outer surface of the walls of the lead chamber, a reservoir at the lower end of said chamber, there being an annular air space about the reservoir, said passages having openings adjacent the lower ends 80 thereof for establishing communication with the external atmosphere and with the annular air space, separate means for controlling the passage of air through the respective openings, and means for directing 85 air under pressure into the annular air space.

6. Apparatus for use in the production of sulfuric acid, including a lead chamber, and a means for creating a natural draft of 90 air along the outer surface of the walls of the lead chamber.

7. Apparatus for use in the production of sulfuric acid, including a lead chamber, and means for setting up a circulation of air as 100 a cooling medium along the outer surface of the walls of the chamber.

8. Apparatus for use in the production of sulfuric acid, including a lead chamber, and separate means for setting up a natural and 105 forced circulation of air respectively along the outer surface of the walls of the chamber.

9. In apparatus for use in the production of sulfuric acid, the combination with a 110 housing, of a lead chamber therein and spaced therefrom, spacing elements extending between the housing and chamber and forming separate air passages extending along the outer surface of the walls of the chamber, a draft flue extending upwardly from the top of the housing and in communication with the upper ends of said air passages, there being air inlet openings in the wall of the housing and close to the 115 lower ends of the air passages, and means for controlling the flow of air through said openings and into the passages.

10. In apparatus for use in the production of sulfuric acid, the combination with 120 a lead chamber, of a housing surrounding the same, spacing and supporting means interposed between the housing and the walls

of the chamber and forming separate air passages, a draft flue extending upwardly from the housing and in communication with the upper ends of the passages, there being openings for the admission of air to the lower ends of the respective passages, and means for controlling the flow of air through said openings.

In testimony that I claim the foregoing as my own, I have hereto affixed my signature in the presence of two witnesses.

THOMAS C. OLIVER.
